HAROLD W. SHONNARD, OF MONTCLAIR, NEW JERSEY, ASSIGNOR TO ELEVATOR SUPPLIES COMPANY, INC., OF HOBOKEN, NEW JERSEY, A CORPORATION OF NEW JERSEY.

DOOR-CONTROL MEANS FOR ELEVATORS.

Application filed December 15, 1927. Serial No. 240,305.

This invention relates to elevators, and particularly to elevators provided with power means for opening and closing the elevator gate and for opening and closing the doors at the various landings as the elevator approaches and stops at such landings.

The present invention provides certain improvements on the invention disclosed and claimed in my co-pending application for improvements in electric door operators, Serial No. 216,808, filed Sept. 1, 1927. Principal among these improvements are, first, the provision of novel and improved mechanical means for transmitting the motion of the elevator gate operating member to the associated landing doors and the landing door operating members, and secondly the provision of a novel arrangement and method of operation of the parts involved in the system, as will become more apparent from the study of the following description when read with reference to the accompanying drawings, wherein:

Figure 1 presents a view in elevation taken from within the elevator and showing the elevator gate and the landing doors at one landing, together with the operating means therefor.

Figure 2 shows a view in elevation of a part of the operating means shown in Figure 1 and comprising principally the means for effecting the transmission of motion from the elevator gate operating means to the landing door operating means; the view being on a scale somewhat larger than the scale of Figure 1.

Figure 3 is a plan view, partly in section along line 3—3 of Figure 2, of the parts shown in Figure 2.

Figure 4 is a view of the parts of Figures 2 and 3 as they appear when the doors are fully open.

Figure 5 is a diagram showing schematically the preferred arrangement and method of controlling the electrical parts and circuits involved in the operation of the system.

Referring to the drawings wherein the preferred embodiment of the invention is illustrated in Figures 1 to 4 inclusive and wherein like reference characters refer to like parts throughout the several views, the character 1 designates an elevator adapted to travel in either direction along the hatchway 2, the elevator being provided with suit-

able suspension means (not shown) adapted to be controlled from the elevator hoisting motor (whose armature H is shown schematically in Figure 5). The elevator hoisting motor is in turn adapted to be controlled through circuits (not shown) operable by the manipulation of the elevator operator's control lever, or car switch, as it is commonly termed in the art, shown at 6 in Figure 1.

The elevator 1 is provided with a gate 7, and as illustrated in Figure 1 the gate is shown as of the collapsible type; but obviously other constructions may be employed. A gate operating arm 8 is shown connecting with the vertically disposed outer plate 9 of the gate 7 by means of a link 10 and pin 11. This operating arm 8 is adapted to be oscillated back and forth to effect opening and closing movements of the elevator gate 7, the means preferably employed for effecting this oscillation consisting of an adjustable rocker plate 12 anchored preferably to the roof of the elevator as indicated at 13, at which location the arm 8 is affixed thereto, preferably by the provision of a pivot pin 15. This rocker plate 12 is in turn adapted to be oscillated or rocked in response to the alternate rotations of the prime mover; the power transmitting means in the preferred embodiment, as shown in Figure 1, consisting of a train of gears 17, 18, 19 and 20, a shaft 21 on which the gear 20 is mounted, a crank 22, and a connecting link 23. The gear 20 is preferably provided with a cam-shaped portion 24 adapted to actuate alternately the switch arms 26 and 27 to open the switches OL and CL respectively, as the gear rotates first in one direction and then the other. The function of these switches will appear hereinafter.

Also, in the preferred embodiment of the invention, means are provided for cushioning the final movement of the elevator gate and the associated landing doors as they approach the final stage of movement in either the opening or closing direction. As shown in Figure 1 such means consists of a double-acting liquid check 25, in which a member is connected so as to have a movement corresponding to that of the gear 20 and prime mover 16. This member has associated therewith means for retarding its progress during its final stage of movement in each direction. The structure of this cushioning

mechanism 25 may, of course, vary to suit the circumstances attending any particular installation, the liquid check just described being that type disclosed and claimed in my 5 co-pending application for an adjustable door operator, Serial No. 93,086, filed March 8th, 1926.

Each landing at which the elevator 1 may stop is provided with a door or doors preferably of the type shown at the landing indicated in Figure 1, where a door is shown consisting of two sections 28 and 29 adapted to slide along in their own planes and in parallel paths to effect an opening and closing of the hatchway 2 at that landing. These doors 28 and 29 are shown in the preferred embodiment as provided with operating arms 30, 31 and 32, or toggle levers as they are commonly termed in the art. As 10 shown, the toggle lever 30 is pivotally mounted on a plate 34 attached to the door 28 at one end, and at the other end is connected by means of a pivot pin 36 to the outer end of the lever 31. Lever 31 is in turn 15 pivotally mounted at a point intermediate its end to a bracket or knee 38 attached to the edge of door 29. The other end of the lever 31 is pivotally connected by means of a pin 40 to the outer end of the lever 32, which 20 is in turn connected at its inner end to a bearing lug 41 mounted on the wall of the shaftway 2 in such a manner as to permit the lever 32 to be swung about the said lug 41 in an upward direction.

With this arrangement it is evident that any motion tending to bend the toggle levers 30 and 31 downward at their point of connection 36 will cause a corresponding upward motion of the right-hand end of the lever 31 25 and of the lever 32. Furthermore, this movement of the toggle levers will draw doors 28 and 29 to the right to permit access to the elevator 1 when stopped at the landing referred to, such motion being imparted 30 to the door 28 through the connecting member 34, and to the door 29 through the connecting bracket 38.

The preferred means for imparting such opening motion to the toggle levers 30 and 31 and consequently to the doors 28 and 29 35 comprises, as shown in Figures 2 and 3, a clutching mechanism consisting of a channel shaped member 50 extending vertically along the plate member 9 of the elevator 40 gate 7 and having its upper and lower portions flared outwardly as indicated at 51 and 52 for a purpose presently to appear. This clutching member 50 is shown as attached to the said plate 9 preferably by the provision 45 of the pin 11. This pin 11 is also utilized as heretofore indicated, as a bearing pin about which the link 10 connecting with the gate operating arm 8 may turn in response 50 to operation of the prime mover 16. To 55 facilitate ready translation of this oscillat-

ing movement of the arm 8 and link 10 into a backward and forward horizontal movement of the clutch channel 50, a roller bearing construction as indicated at 56 is employed.

Adapted to be engaged in the pocket of the channel member 50 when the car 1 arrives opposite thereto from either direction is a roller 60 connecting with the toggle lever 30 by means of a suitable angular 60 bracket or bell crank 61, in which the roller 60 is free to turn about its own center pin 62, the latter being in turn eccentrically mounted on the circular stud 63 to which the bell crank 61 is secured by means of a nut 64. 65 This eccentric construction permits of adjustment to insure perfect alignment of all rollers along the hatchway 2 with the channel 70 50. It is thus possible to so adjust the roller at the various landings along the hatchway 2, corresponding to the roller 60 at the landing illustrated in the drawings, that the elevator 1 may pass up and down the hatchway without any collision or contact taking place between the sides of the channel member 50 and the successive rollers along the hatch similar to the roller 60. To assist in securing such a desirable result a slight clearance, as indicated in Figure 2, 75 is allowed between the roller 60 and the edges of the channel member 50. With this arrangement it will be apparent that contact between the channel member 50 and the roller 60 will occur only when the elevator stops opposite the said roller 60 and an 80 opening movement is imparted to the gate 7 thru the operation of the gate operating motor 16.

The bell crank 61 constitutes the means for causing the motion thus imparted to the roller 60 to be transferred to the toggle lever 30 and the doors 28 and 29 to cause the downward swing of the said toggle lever and a corresponding sliding movement of the doors 28 and 29 toward the open 90 position.

In connection with the door driving mechanism just described, attention is directed to the advantages which the construction shown in Figures 2, 3 and 4 enjoy over former constructions employed for an equivalent purpose. By the use of the link 10 pivoted to swing freely at either end, the flared channel 95 50 and the eccentrically mounted roller 60, the possibility of any serious disalignment between the members mounted in the hatchway and those on the elevator is eliminated, as is likewise the possibility of any collision between such parts. Furthermore, by the use of a construction whereby 100 the door operating force is applied to a swinging lever, such as the bell crank 61 or lever 30, a far greater smoothness and 105 flexibility of operation is attained with a far less expenditure of effort than is re- 110

quired when the force is directed against the hatchway doors directly—and here again the possibility of straining or distorting any mechanism associated with the doors is reduced to a minimum.

Having now described the principal mechanical parts involved, the electrical parts and circuits remain to be considered.

These are not claimed herein however, for the reason that they constitute part of the subject matter of the co-pending application, Serial No. 240,304, filed jointly by Harold J. Fear and myself, on even date herewith, and bearing a similar title. The invention herein claimed, however, is preferably (though not necessarily) employed in conjunction with electrical and electro-mechanical control means of the type shown in Fig. 5, and, therefore, a description of such control means is included herein.

Referring to Figure 5 reference character 103 designates a relay used for controlling the initiation of operation of the electrical prime mover 16. As shown in Figure 5 by way of illustration of the preferred embodiment the relay 103 is inserted in a circuit passing from the trunk feeds 101 and 102 through a set of contacts 105 and 106 preferably located within the elevator 1 in such a position as to be normally closed while the operator's control lever 6 is in either running position; in other words, the circuit to the relay 103 is closed at the points 105 and 106 at all times while the car is progressing in normal manner along the hatchway 2 in either direction, and so as to adapt the system to elevators provided with "leveling" or gradual stopping and starting means, the circuit through the relay 103 preferably passes by means of a parallel branch through a set of contacts 107 and 108, these contacts being normally closed by operation of relay 109 connected in parallel with the elevator hoisting motor armature H. With this arrangement it will be obvious that the circuit through the relay 103 will be closed by means of this branch circuit just referred to so long as the hoisting motor armature H remains energized, and irrespective of any movement imparted to the operator's control lever 6 for the purpose of bringing the same to the neutral position as a preparatory measure to stopping the elevator.

With control means arranged as just described it will be evident that, as the elevator approaches a floor where a stop is to be made, as for example, the floor at which the doors 28 and 29 are located, the throwing of the elevator operator's control lever 6 to the neutral position will have no effect upon the continued energization of the relay 103 except to shunt the circuit passing therethrough to the branch including the contacts 107 and 108. After the decelerating circuits or other means provided for gradually bringing the

motor H to a stop have operated in response to the centering of the control lever 6, the resultant de-energization of the relay 109 permits the contacts 107 and 108 to separate thereby opening the circuit through the relay 103 and de-energizing said relay.

The de-energization of relay 103 which is thus produced functions to close the contacts 112 and 113 upon each other thereby closing a circuit to the relay 115, this circuit passing as follows: from side B of the three phase source of current through conductor 116, conductors 119 and 120, contacts 113 and 112, conductor 121, switch OL (which in the position of the gear 20 as shown is closed), thence through conductor 125 to the relay 115, thence back to side C of the source of current thru the conductor 127. The energization of relay 115 thus produced functions to cause a closing of the directional switches O¹, O² and O³. The closing of the directional contacts O¹, O² and O³ thus effected, produces an energization of the operating windings of the door operating motor 16. As shown herewith by way of illustration, the motor is wound as a three phase alternating current machine. Obviously other types of electric prime movers may be utilized. The energization of the door operating motor 16 thus brought about causes a commencement of the opening movement of the elevator gate, and also, through the mechanical connections heretofore described, a corresponding movement of the hatchway doors 28 and 29. Now as the rotation of motor 16 brings the gear 20 to the predetermined point in the door-opening movement, the contacts CL are moved to closed position by action of the cam 24 previously described. The closing of the contacts CL thus brought about closes a circuit to energize the relay 140, this circuit passing as follows: from side C of the line through conductor 127, relay 140, conductor 141, switch CL, conductors 142 and 119 back to side B of the line. The energization of relay 140 thus produced serves to close the normally open contacts 140^b.

Now, as the continuing opening movement of the doors in response to the energization of the door operating motor 16 brings the cam 24 on gear 20 into position to open the contacts OL, this opening of the said contacts causes an opening of the circuit passing therethrough to the door opening relay 115, thereby de-energizing the said relay. The de-energization of this relay 115 causes a dropping out of the directional contacts O¹, O² and O³, thereby de-energizing the motor windings. Immediate stopping of the motor, however, does not follow because of the momentum gathered by the rotating parts of the motor while operating. This momentum is sufficient to carry the elevator gate and associated hatchway doors 28 and 29 to their full open positions.

Now, when it is desired to start the elevator away from this landing, and, pursuant to this intention, the operation of the elevator hoisting mechanism is again initiated 5 through the control lever 6, the consequent closing of the contacts 105 and 106 causes a return of the circuit through the relay 103. The energization of relay 103 which is thus effected permits the contacts 112 and 113 to 10 open and the contacts 113 and 114 to resume their normally closed condition. The closing of the contacts 113 and 114 thus brought about functions to complete the circuit passing through the previously closed contacts 15 140^b to the door closing relay 155. The completion of this circuit and the consequent energization of the relay 155 causes a closing of the directional contacts C¹, C² and C³, thereby energizing the motor windings to 20 cause rotation of the motor 16 in the reverse direction to that previously produced. The resulting rotation of the motor 16 causes the elevator gate and the associated doors to commence their movements toward closed 25 position, and incidentally causes a corresponding rotation of the gear 20. When this rotation has proceeded the predetermined amount necessary to close the contacts OL, the occurrence of this operation 30 has no immediate effect upon the circuit passing therethrough since the said circuit remains open at the contacts 112 and 113 as previously pointed out. The further rotation of the motor 16 and corresponding rotation 35 of the gear 20 causes, after the predetermined movement, an opening of the contacts CL. This opening of the contacts CL breaks the circuit to the relay 140, thereby opening the contacts 140^b. This opening of 40 the contacts 140^b breaks the circuit to the relay 155, as is plainly evident from the diagram of Figure 5 thereby permitting the directional switches C¹, C² and C³ to resume the open position, thereby breaking the path 45 of current to the motor 16 which has heretofore passed through the contacts C¹, C² and C³.

The remaining portion of the door closing movement is assisted considerably by the 50 provision of the weight 90 attached to the bar 91 secured to the toggle lever 32 in the manner shown in Figure 1. As shown in this figure the disposition of the weight is such as to tend to bring the toggle levers 55 back to their horizontally aligned positions, thereby tending to bring the doors 28 and 29 to their fully closed positions.

The conditions last described prevail until the control lever 6 is again manipulated for 60 the purpose of stopping the car at a succeeding landing. When this occurs the cycle of operations heretofore carried through is again inaugurated.

The above specification and the annexed 65 drawings are to be considered only as illus-

trative of what I deem the preferred embodiment at this time. The invention is not limited to this specific form or to any particular combination or application of the parts, but embraces all modified forms and 70 constructions within the scope of the appended claims.

I claim:

1. In combination with an elevator gate and a landing door, a channel-shaped member on said gate, means on the elevator for moving said channel-shaped member and gate in unison, and means connecting with said landing door for moving said door in unison with said gate, said means comprising a door actuating lever and a supporting pin therefor on said door, a roller adapted to be engaged by said channel-shaped member and mounted to swing about said supporting pin, and a bell-crank connecting said roller and lever to produce corresponding swinging movements of said roller and lever about said supporting pin, the swinging of said bell-crank and lever causing a corresponding sliding movement of said door. 80

2. In combination with an elevator gate and a landing door, a member projecting outwardly from said gate and movable therewith, means on the elevator for opening said gate, and means for moving said landing door in unison with said gate comprising a door actuating lever, means on said door for supporting said lever, a bell-crank secured to said supporting means and to said lever whereby movement of said bell-crank about said supporting means produces a corresponding movement of said lever and a resultant opening movement of said door, and means for imparting the motion of said 100 gate member to said bell-crank. 105

3. In combination with an elevator gate and a landing door, a member projecting outwardly from said gate and movable therewith, means on the elevator for opening said gate, and means for moving said landing door in unison with said gate comprising a bell-crank, means on said door for supporting said bell-crank, said means also serving as the driving connection between said bell-crank and said door, and said outwardly projecting member serving to swing said bell-crank about its supporting means in response to the operation of said gate opening means. 110 115

4. In combination with an elevator gate and a landing door, a member projecting outwardly from said gate and movable therewith, means on the elevator for opening said gate, and means for moving said landing door in unison with said gate comprising a lever and means on said door for supporting said lever, said means also serving as the driving connection between said lever and said door, and said outwardly 120 125 130

- projecting member serving to swing said lever about its supporting means in response to the operation of said gate opening means.
5. In combination with an elevator gate and a landing door, a member projecting outwardly from said gate and movable with said gate, means on the elevator for opening said gate, and means for moving said landing door in unison with said gate comprising a lever pivotally connected to said landing door and a member attached to said lever and adapted to serve as the driving connection between the outwardly projecting member on the elevator and said pivotally connected lever on the landing door, said outwardly projecting member operating to swing said lever in response to the operation of said gate opening means.
6. In combination with an elevator gate and a landing door, a member projecting outwardly from said gate and movable therewith, means on the elevator for opening said gate, and means for moving said landing door in unison with said gate comprising a lever having a pivotal connection with said landing door whereby swinging movement of said lever causes proportionate opening movement of said landing door, a motion transmitting member associated with said lever in proximity to said pivotal connection, and means for causing the outwardly projecting member on the elevator to engage said motion transmitting member to swing said lever about said pivotal connection in response to the operation of said gate opening means.
7. In combination with an elevator gate and a landing door, a member projecting outwardly from said gate and movable therewith, means on the elevator for opening said gate, and means for moving said landing door in unison with said gate comprising a lever and means on said door for supporting said lever, said means also serving as the driving connection between said lever and said door, and said outwardly projecting member serving to swing said lever about its supporting means in response to the operation of said gate opening means, and means for preventing any engagement between said outwardly projecting member on the elevator and said motion transmitting member associated with the landing door until the operation of said gate opening means is inaugurated.
8. In combination with an elevator gate and a landing door, a member projecting outwardly from said gate and movable therewith, means on the elevator for opening said gate, and means for moving said landing door in unison with said gate comprising a lever having a pivotal connection with said landing door whereby swinging movement of said lever causes proportionate opening movement of said landing door, a motion transmitting member associated with said lever in proximity to said pivotal connection, and means for causing the outwardly projecting member on the elevator to engage said motion transmitting member to swing said lever about said pivotal connection in response to the operation of said gate opening means, and means for preventing any engagement between said outwardly projecting member on the elevator and said motion transmitting member on the landing door during the normal passage of the elevator past said landing door.

Signed at Hoboken, in the county of Hudson and State of New Jersey this 14th day of December, A. D. 1927.

HAROLD W. SHONNARD.
